PAGE 2

FIG. 4

FIG. 7

FIG. 5

FIG. 6

FIG. 8

FIG. 9

FIG. 10

FIG. 11

FIG. 12

FIGURE 1 is a perspective view of a furniture leg, showing my new design;

FIGURE 2 is a view in front elevation of the leg of FIG. 1;

FIG. 3 is a side elevational view of the leg of FIG. 2; FIG. 4 is a rear elevational view of the leg of FIGS. 2 and 3;

FIG. 5 is a plan view of the leg of FIG. 3 along the line 5-5 thereof;

FIG. 6 is a view in horizontal section along the line 6-6 of FIG. 3;

FIG. 7 is a view in horizontal section along the line 7-7 of FIG. 3;

FIG. 8 is a front elevational view of a leg showing a modification of my new design;

FIG. 9 is a side elevational view of the leg of FIG. 8;

FIG. 10 is a rear elevational view of the leg of FIGS. 8 and 9;

FIG. 11 is a top elevational view as seen in the direction of the arrows along the line 11-11 of FIG. 9; and

FIG. 12 is a view in horizontal section along the line 12-12 of FIG. 9.

I claim:

The ornamental design for a furniture leg, substantially as shown.
